BY *Almon C. Brown*,
ATTORNEY

UNITED STATES PATENT OFFICE.

GEORGE A. GAGE, OF TULSA, OKLAHOMA.

SELF-CLEANING CUP RING.

Application filed August 13, 1928. Serial No. 299,299.

My invention relates to plungers for well pumps and more particularly to cup rings employed on a plunger for spacing and securing the packing cups in proper spaced relation on a plunger stem; the principal object of the invention being to eliminate sand or sediment which may pass into the joints between the rings and the stem, and thereby prevent binding of the rings on the stem so that the rings may be easily and quickly removed for the replacement of worn parts of the plunger.

In accomplishing these and other objects of the invention, I have provided improved details of structure the preferred forms of which are illustrated in the accompanying drawings, wherein:

Fig. 1 is a fragmentary sectional view of a pump barrel showing a plunger therein fitted with my improved cup rings.

Fig. 2 is a perspective view of a plunger with the cup members and one of the cup rings shown in section to better illustrate their mounting on the plunger stem, and the valve cage being partly broken away to disclose the plunger.

Fig. 3 is a transverse section on the line 3—3, Fig. 2 showing the slots in a cup ring communicating with the walls of the plunger stem.

Fig. 4 is a detail perspective view of one of the cup rings.

Referring in detail to the drawings:

1 designates a portion of an ordinary well pump including a pump barrel 2 and a plunger 3, which when the pump is installed in a well for operation, is reciprocable in the barrel by means of the usual sucker rods connected with actuating means (not shown) at the top of a well.

The plunger 3 includes a tubular stem 4 carrying a valve cage 5 and a series of spaced packing units 6 including my improvements for sealing the plunger in its working relation with the barrel.

Provided at opposite ends of the stem 4 are threaded portions 7 and 8 and formed slightly below the upper threaded portion 8 is a collar portion 9 providing a stop shoulder 10 which serves to retain the upper packing unit on the stem.

The packing units 6 include packing cups 11 and cup rings 12 mounted on the portion of the stem below the stop shoulder 10 in alternate order as presently described.

The packing cups 11, preferably constructed of leather, have central openings 13 for receiving the stem 4, and in assembly the open ends of the cups are directed upwardly, the upper cup of the series receiving the collar portion 9 and having its bottom in abutment with the shoulder 10, and its side walls extending over a substantial area of the collar portion 9 for retention in sealing relation with the walls of the pump barrel.

Next in order of assembly below the upper packing cup is a cup ring 12 having an upper portion 14 substantially equal in diameter to the outside diameter of a packing cup, and a lower portion 15 adapted to fit the interior of a packing cup, said portions being connected by an annular concave web-like portion 16. A central opening 17 in the ring receives the stem 4 and a tapered counterbore 18 at the upper end of the ring is adapted for seating the bottom of a superimposed packing cup as shown in Fig. 2.

Formed in the concave wall portion 16 of the ring are angularly disposed slots 19 communicating with the central opening 17, the slots being preferably arcuate and equally spaced and inclined in the same direction relative to the periphery of the ring, so that relatively narrow slots extending at an inclination from the vertical may provide the equivalent of a horizontal slot extending circumferentially over a relatively large portion of the web 16. The ring thus slotted is adapted for permitting the escape of sand or sediment which enters the opening 17 and passes downwardly between the ring and the stem when the plunger is in operation.

The additional packing units comprising the sealing element of the plunger are composed of rings and cups identical in construction to those above described assembled on the stem in alternate order and securely retained on the stem below the collar portion 9 by nuts 20 engaging the threaded portion 7.

The valve cage 5 mounted on the upper end of the stem 4 by its threaded engagement with the threaded portion 8 includes the usual pin 21 whereby the plunger is connected with the actuating sucker rods, and a ball check valve 22 in the cage cooperates with a seat 23 for preventing return flow of fluid through the plunger when it is in operation.

Cup rings of the character described may be mounted on a plunger stem to space the cups and will serve as cup spacers in the usual manner. When the plunger is operated more or less sedimentary matter such as sand may lodge on the stem adjacent the ring and tend to pass inwardly of the bore thereof between the ring wall and the stem. When the plunger is dismantled for repairs and replacements, sliding of the rings over the stem causes the rings to move over the sedimentary particles, and these particles are discharged from the rings through the slots. The angular positions of the slots 15 extending in a circumferential direction provide that the particles are effective for binding the rings over a relatively short path, and escape before they have seriously impeded the movements of the rings or caused 20 extensive damage to the stem and rings.

What I claim and desire to secure by Letters Patent is:

1. In combination with a plunger for well pumps including a stem and packing cups 25 on the stem, cup rings on the stem for spac-

ing said cups having arcuate slots in their side walls for relieving sediment, to prevent binding of the rings on said stem.

2. In a plunger for well pumps including a stem having a through channel, and packing cups on the stem, cup rings on the stem for spacing said cups and having angularly disposed slots in their walls communicating with the walls of said stem for relieving sediment and thereby preventing binding of 35 said rings on said stem.

3. In a plunger for well pumps including a stem and packing cups on the stem, cup rings on the stem each having a cup-receiving tapered seat, a central opening receiving said stem, and ports communicating with said opening for passage of sediment from the opening. 40

4. A ring for the purposes described comprising a body having a concave outer face, an axial opening, and similarly inclined slots 45 communicating with said opening.

In testimony whereof I affix my signature.

GEORGE A. GAGE.
